UNITED STATES PATENT OFFICE.

ONESEME LANDRY, OF NEW BEDFORD, MASSACHUSETTS.

FILLING-FEELER MECHANISM FOR AUTOMATIC LOOMS.

1,420,560.

Specification of Letters Patent. Patented June 20, 1922.

Application filed July 12, 1920. Serial No. 395,548.

To all whom it may concern:

Be it known that I, ONESEME LANDRY, a citizen of the United States, residing at New Bedford, in the county of Bristol and 5 State of Massachusetts, have invented certain new and useful Improvements in Filling-Feeler Mechanism for Automatic Looms, of which the following is a specification.

This invention relates to certain new and 10 useful improvements in a filling feeler mechanism for automatic looms, and it has for its primary object and aim to provide sensitive means for causing the filling bobbin, or cop, to be changed when the yarn 15 thereon is used up or nearly so.

A further object is to provide an intermittent action for ascertaining, at intervals, the condition of the supply of yarn on the bobbin or cop so that constant or continuous 20 engagement with the bobbin yarn, together with the incidental wear and tear, is obviated.

The invention further resides in the features of construction and the arrangement 25 and combination of parts hereinafter described and claimed, reference being had to the accompanying drawings; wherein—

Figure 1 is a fragmentary top plan view of the improved mechanism;

30 Figure 2 an end elevation thereof;

Figure 3 an enlarged plan view of the feeler device; and

Figure 4 a detailed elevation of the arm attached to the front shaft of the loom.

35 The improved construction is especially adapted for that type of looms known as the "Draper automatic loom," wherein the shuttle containing the bobbin moves lengthwise in the lay of the loom when the lay 40 of the loom is at rear center or the point of its swing farthest away from the feeler. When the shuttle has entered the box, the lay swings forward to place the thread just laid, by the passage of the shuttle, up 45 against the part of the cloth already woven. Referring to the accompanying drawings, a holder 1 is secured to the bracket of the loom which holds the shipper handle and slidably supports a feeler support 2 which 50 is urged outwardly by a coiled spring 3 housed within the guideway and chamber 4 of said holder. A feeler 5 is pivoted to the slidable support 2 by a bolt 6 about which a coiled spring 7 encircles for urging the 55 feeler to be left in Figure 3. The outer end

of the feeler is curved in the opposite direction and formed on its outer side with serrations 8 which are designed to catch in the yarn 9 on the bobbin or cop 10 and hold the feeler from riding off to the right about 60 its pivot. The inner end 11 of the feeler, here depicted as a detachable part, constitutes an inwardly extending feeler finger which, when the supply of yarn on the bobbin is substantially or altogether depleted, 65 will be swung to the left by reason of the feeler 5 contacting directly with the body of said bobbin and riding off the same to the right since there is no yarn for the serrations to engage in.

70 By this swinging movement to an operative position, the feeler finger 11 is disposed in the path to engage a lug 12 when the feeler support is pushed inwardly by the bobbin. Lug 12 is carried on one end 75 of a lever 13 that is pivoted intermediate its ends and has its opposite end engaged in a curved slot 14 of an arm 15. This arm is attached to the shaft 16 at the front of the breast beam of the loom and is a part of 80 the loom equipment.

In operation, the feeler, being in such position that it will enter the shuttle through a slot in the side thereof when the lay of the loom is on the forward swing, will come 85 in contact with the yarn on the bobbin, or cop. The curve of the feeler is so arranged that as long as there is yarn on the bobbin or cop, the point of contact between the feeler and the yarn will be back from the 90 point of the feeler, causing the serrations to engage in the yarn and the feeler to be pushed back with its support without rocking on the stud 6. The feeler finger 11 will thus be held out of the path of and out of 95 contact with the lug 12 on the rod 13. When the yarn on the bobbin or cop is reduced to a minimum point the end of the feeler will strike on the hard body of the bobbin or cop and ride thereoff to swing 100 the feeler on its stud and move the feeler finger to the left where it will contact with the lug 12 on the rod as the support 2 is moved backwardly. This causes the rod to swing on its pivot 17 and the outer end to 105 raise the arm 15 by moving in the curved slot 14. The raising of this arm brings it in contact with the lay of the loom which forces it back, giving a movement to the shaft to which it is connected, and this shaft 110

is connected to a system of levers which actuate the filling change mechanism in the battery, not shown.

If the feeler were permitted to make a contact with the yarn for every two picks of the loom unnecessary wear, both on the yarn and on the mechanism of the feeler, would occur. Therefore, mechanism has been provided to hold the feeler out of contact for a definite period, as for instance sixty picks, which period can be varied for any number required, then permit the feeler to engage the yarn for two picks. This is accomplished in the following manner.

15 Along one edge of the feeler slide 2 are cut ratchet notches 18 which are engaged by a pawl 19, the same being pivoted on a vertical stud 20 having a spiral spring 21 thereabout to keep the pawl in contact with the notches or teeth 18. The outer end of this pawl carries a pin 22 extending vertically downward. A horizontal shaft 23 is provided on one end with a gear 24 that is driven by gears not shown, from the mechanism of the loom and on the opposite end with radiating pins or arms 25 which contact with the trip or pin 22 causing the pawl to release the feeler. The spring 3 then brings the feeler into contact with the bobbin yarn. By the time the pin 25 has released the pawl the latter springs back into engagement with the teeth of the slide and holds the feeler out of contact with the yarn and bobbin. This period of contact can be governed by the time of contact of the two pins and is usually set for two picks of the loom.

The construction is exceedingly simple and automatic in operation. The device, 40 also, can be applied to the specified type of loom without material modification or reconstruction of the latter. The "feeling" is predetermined, very sensitive and can be for longer or shorter rest periods with corresponding shorter and longer active periods.

The feelers at present in use can not be adjusted fine enough to work unless there is some small amount of yarn on the bobbin,

and this yarn is all wasted; the present improvements can be adjusted to work when 50 there is the last layer of yarn on the bobbin, thus saving the waste. Furthermore it will work equally well on wooden bobbins or paper cops.

The feeler can be arranged at either end 55 of the loom.

What is claimed is:—

1. In a feeler device for looms, a support having a guideway, a spring tensioned slide in the guideway, a feeler pivoted to one end 60 of the slide and extending outwardly therefrom, ratchet teeth carried by a side of the slide, a pawl pivoted between its ends and having one end engaging the ratchet teeth and having a projecting part on its opposite 65 end and an intermittently rotating element having spaced projections for successively acting on the projecting part of the pawl to move the pawl out of engagement with the ratchet teeth at predetermined intervals. 70

2. A feeler device for looms, comprising a support, a slide member guided thereon and formed on one edge with a series of notches, means urging the slide extended, a feeler carried by the slide member, a spring- 75 pressed pawl pivoted between its ends and engageable at one end in the notches to hold the slide member retracted, a pin depending from the opposite end of the pawl, and an intermittently rotating wheel having radiat- 80 ing arms for successively acting on the pin to retract the pawl at predetermined intervals.

3. In a feeler device for looms, a support having a guideway, a feeler pivoted to the 85 slide, ratchet teeth carried by the slide, a pawl pivoted between its ends and having one end engaging the ratchet teeth and having a projection on its other end, and intermittently actuated means having spaced 90 parts for successively acting on the projection of the pawl to move the pawl out of engagement with the ratchet teeth at predetermined intervals.

In testimony whereof I affix my signature. 95
ONESEME LANDRY.
